UNITED STATES PATENT OFFICE

2,582,168

ADJUSTABLE COLUMN FORM

Takeo Sato, Honolulu, Territory of Hawaii

Application June 14, 1948, Serial No. 32,971

8 Claims. (Cl. 25—131)

1

This invention relates to portable concrete forms of the type adapted to be assembled in the field, removed after use, and reused and in particular adjustable forms for casting concrete columns in place wherein the columns may be square, or rectangular and substantially of any size in cross section, or of any height.

The purpose of this invention is to provide portable concrete forms which may readily be set up in the field and readily removed in which the same parts may be used to form columns of different sizes.

Portable metal forms are necessarily heavy and when used for large and high columns it is difficult to handle sections of portable forms now in use. With this thought in mind this invention contemplates forms having a plurality of vertically disposed sections in which the sections are formed of comparatively thin metal reinforced at the edges and at points intermediate of the edges with structural shapes so that the weight thereof is reduced to a minimum.

In assembling and dismantling portable concrete forms time is essential and for this reason the usual bolts and nuts are objectionable, and to overcome this object the forms of this invention use studs with slots therethrough and tapered keys that may be driven into the slots and which may readily be removed by tapping.

In some cases it is also desirable to shore up the lower ends of column forms and with this thought in mind this invention includes shoring blocks with sloping intermediate surfaces and studs and keys for securing sections of the blocks together.

It is also desirable to provide extensions at the upper ends of column forms for holding wood sections and to accomplish this the invention includes means for attaching uprights to the upper ends of the forms to which boards may be attached.

The object of this invention is, therefore, to provide a complete portable form for casting concrete columns in position that is relatively flexible in that it may readily be adjusted to different sizes and shapes.

Another object of the invention is to provide a portable column form that is adjustable and that may be set up and dismantled in a comparatively short time.

A further object of the invention is to provide an adjustable portable concrete form which is of a simple and economical construction.

With these and other objects and advantages in view the invention consists of the new and useful combination, construction, and arrangement

2

of parts as hereinafter more fully described, set forth in the claims appended hereto, and disclosed in the accompanying drawings forming part hereof, wherein:

5 Figure 1 is a view showing a side elevation of a typical form with the attaching elements extending from the sides thereof and with parts broken away.

10 Figure 2 is a cross section taken on line 2—2 of Figure 1 showing a typical section through the form with the parts assembled to cast a square column.

Figure 3 is a similar section showing the parts set up to form a rectangular-shaped column.

15 Figure 4 is a section similar to that shown in Figure 2 showing the parts assembled to form a comparatively small square column.

Figure 5 is a detail showing a front elevation of the attaching bar with other parts omitted.

20 Figure 6 is a similar view showing the back of the bar.

Figure 7 is a view showing an end elevation of the bar.

25 Figure 8 is a perspective view illustrating the attaching bar.

Figure 9 is a view illustrating one of the side plates of the form with parts broken away.

Figure 10 is a sectional plan similar to that shown in Figure 2 with parts broken away, and 30 illustrating extension sections used with the side plates.

Figure 11 is a detail illustrating an angle clip used with the attaching bars.

Figure 12 is a view looking toward the opposite 35 side of the clip.

Figure 13 is a detail illustrating a filler block attached to an end of one of the sections of the form, and with parts broken away.

Figure 14 is a section through two of the 40 sections of the form illustrating means for connecting the sections.

Figure 15 is a detail showing one of the connecting studs with a slot therethrough.

Figure 16 is a detail showing a key in a slot in a 45 stud with part of the stud broken away and shown in section.

Figure 17 is a side elevational view showing the lower end of a column form with parts broken away and illustrating a shoring single wedge at 50 the lower end of a column form.

Figure 18 is a plan view of a column form with part broken away showing the shoring wedge.

Figure 19 is a cross section through the shoring wedge taken on line 19—19 of Figure 18.

55 Figure 20 is a similar section taken on line 20—20 of Figure 18.

Figure 21 is also a similar section taken on line 21—21 of Figure 18.

Figure 22 is a view showing a front elevation of the upper section of the shoring wedge with parts omitted and parts broken away.

Figure 23 is a similar view showing the lower member of the wedge.

Figure 24 is a view showing a corner of the upper section of the shoring wedge with an adjusting angle bar extending therefrom and with parts broken away.

Figure 25 is a similar view of the lower section of the wedge with parts broken away and parts omitted.

Figure 26 is a perspective view with parts broken away illustrating the relative positions of the upper and lower sections of the shoring single wedge.

Figure 27 is a detail illustrating an extension at the upper end of the form.

Figure 28 is a view showing a side elevation of the upper end of a form showing a plurality of extension members as shown in Figure 27 and with parts broken away.

Figure 29 is a view showing a side elevation of one end of a form with extension members secured thereto by countersunk head studs, and with parts broken away.

Figure 30 is a cross section through one side of a form taken on line 33—39 of Figure 28.

Figure 31 is a detail illustrating a corner of a side of the form shown in Figure 28 showing an opening to accommodate an extension member.

Figure 32 is a detail illustrating an extension member with clip angles in the ends thereof and with parts broken away.

Referring now to the drawings wherein like reference characters denote corresponding parts the adjustable column form of this invention includes, primarily side plates 10, attaching bars 11, holding plates or clip angles 12, studs 13, keys 14, shoring wedge sections 15 and 16, and extension members 17.

The side plates 10 are reinforced by angles 20 and 21 at the sides, T-bars 22 intermediate of the ends, and flanges 23 and 24 at the upper and lower ends, respectively. The outwardly extending legs of the angles 20 and 21 are provided with stud holes 25 and 26, respectively, and the flanges 23 and 24 are provided with stud holes 27 and 28 and nail holes 29 and 30, respectively.

The width of the side plates 10 corresponds with that of a common column, however, when it is desired to cast larger columns extension plates 31 with angles 32 and 33 at the sides may be used and the outstanding legs of the angles are provided with stud holes spaced to correspond with the holes of the angles 20 and 21 so that they may be secured in position by the studs and keys as illustrated in Figure 10.

The attaching bars 11 are formed as shown in Figures 5 to 8, inclusive, with a web 34 on one side and ribs 35, 36 and 37 on the other, and with openings 38 between the ribs and lugs 39 and 40 on a head 41 at one end. As shown in Figures 2, 3, and 4, the head 41 is positioned against the inner surface of the outstanding legs of the angles 20 and 21 with the lugs 39 and 40 in the holes therein, and the holding plates 12 are positioned against the ribs and outer surfaces of the angles, and these parts are clamped together by the studs 13 and keys 14. The plates 12 are provided with flanges 42 having lugs 43 and studs 44 thereon and the studs 44 are provided with slots 45 to

receive the keys 14. The clip angles or plates 12 are also provided with openings 46 that register with the openings 38 in the bars 11.

The studs, as shown in Figures 15 and 16, are formed with heads 27 and slots 48 extend through the shank portions thereof which receive the keys 14. In assembling the forms the studs are placed through the holes and the keys are driven into the slots so that the parts are positively secured together, and when taking the forms down it is only necessary to tap the keys on the small ends to release the parts.

Figure 13 illustrates a wood filler or anchoring block 49 at the end of a side plate and the block is secured in place by nails 50 with the side plate secured thereto by nails 51, and in Figure 14 the flange 24 of one side plate is secured to the flange 23 of another by the studs 13 and keys 14. The side plates may be attached together, or to wood blocks as may be desired.

The shoring wedge elements at the lower end of the column forms are illustrated in Figures 18 to 26, inclusive, wherein the base flange 52 of the lower section 16 is secured to the concrete floor 53 by bolts 54, and the section is formed with end ribs 55 and intermediate ribs 56. The upper surfaces of the ribs slope downwardly from the inner walls of the sections and the intermediate ribs 56 are provided with studs 57 that have key openings 58 therein. The upper section 15 is formed with an outwardly extending web 59 and, as illustrated in Figure 22, this section is provided with tabs 60 and 61 on the ends of webs 62 and 63, respectively, that extend downward over the lower section, and the ends of the tabs are provided with holes 64 and 65 through which the studs 57 extend. The upper and lower sections are secured together by the studs with the keys 14 secured to the lower flange 24 of the side plate 10 by studs 13 and keys 14.

The shoring wedge elements are also adjustable with the form and one end of each of the upper sections 15 is provided with an outwardly extending angle bar 66 having stud holes 67 therein, and the angle bars of one section are secured to the adjoining sections by bolts 68 with keys 69, as shown in Figure 18. The inner ends of the angle bars 66 are provided with the flanges 70 having lugs 71 thereon that are positioned in openings 72 in the vertical legs of the sections 16 when the parts are assembled. The bolts 68 extend through the holes 67 in the angles 66 and through holes 73 in the tabs 60 and 74 in the vertical webs 75 of the angles 15. The lower edges of the webs 62 and 63 are inclined to correspond with the upper edges of the ribs 55 and 56 of the lower section, and the web 59 of the upper section and the base 52 of the lower section 16 are provided with nail holes 76 and 77, respectively.

The forms may also be provided with extension members 17 as shown in Figures 27 to 32, inclusive, and these are formed with angles having stud holes 78 in one leg and nail holes 79 in the other and the ends are provided with clip angles 80 and 81 with stud holes 82 in the sides thereof and holes 83 in the ends. In this design the end flanges 84 of the side plates 85 are provided with openings 86 through which the members 17 extend, and the flanges 87 and 88 at the edges of the side plate are provided with countersunk openings 89 and 90 respectively, to receive the countersunk heads of stud 91 which have slots 92 to receive keys 93, similar to the keys 14. The

5

stud holes in the intermediate flanges of the side plates are not countersunk as they receive the studs 13 as shown. The extension members may be mounted on the ends of the side plates as shown in Figure 28 with the upper ends secured to a member 94 by screws 95 and boards 96 may be secured thereto with the inner surfaces flush with the inner surface of the side plate 85.

The forms may, therefore be assembled in various combinations to form columns of different shapes and sizes and the parts may readily be set up and also readily dismantled.

It will be understood that other modifications may be made in the design and arrangement of the parts without departing from the spirit of the invention.

What is claimed is:

1. An adjustable form for concrete columns comprising a plurality of side plates having permanently attached angles on the side edges and flanges at the ends with spaced holes in outstanding legs of the angles and also in the flanges at the ends, removable attaching bars positioned in holes in the outstanding legs of the angles and having openings therein, holding plates with flanged ends positioned against the attaching bars and outstanding legs of angles of adjoining side plates, and studs with keys therethrough clamping the side plates together through the said attaching bars and holding plates.

2. An adjustable form for concrete columns comprising a plurality of rectangular-shaped side plates with flanges at the sides and ends and having openings in the flanges, attaching bars removably mounted on the flanges of the side plates, holding plates with flanged ends positioned against the attaching bars and flanges of adjoining side plates, and studs with keys therethrough clamping the side plates together through the said attaching bars and holding plates.

3. An adjustable form for concrete columns comprising a plurality of side plates having permanently attached angles on the side edges, T-bars intermediate of the edges and flanges at the ends with holes in outstanding legs of the angles and also in the flanges, removable attaching bars having lugs positioned in the holes of the outstanding legs of the angles and having ribs thereon with openings between the ribs, holding plates with flanged ends positioned against the attaching bars and outstanding legs of angles of adjoining side plates, studs having heads and slots through the shanks thereof positioned through the holding plates and attaching bars, and tapering keys in the slots of the studs clamping the parts together.

4. Attaching bars for metal concrete forms having side and end plates with flanges having spaced bolt holes therein on the edges, comprising ribbed plates with perpendicularly positioned heads with studs on the heads positioned to register with the bolt holes of the flanges of the side and end plates and having spaced bolt holes between the ribs.

5. Attaching bars for metal concrete forms having side and end plates with flanges having spaced bolt holes therein on the edges, comprising ribbed plates with perpendicularly positioned heads with studs on the heads positioned to register with the bolt holes of the flanges of the side and end plates and having spaced bolt holes between the ribs, and holding plates positioned against the ribs of the said ribbed plates and

6

overlapping flanges of the said side and end plates.

6. In a collapsible and adjustable concrete form, the combination which comprises side plates having flanged ends with angles having outwardly extended perforated flanges secured to the side edges and with longitudinally disposed T-bars permanently secured to the plates and positioned midway between the angles on the side edges thereof providing an elongated shallow tray with a reinforcing member extended longitudinally through the center, attaching bars having perforated flanges extended at right angles from the sides of said plates, clip angles positioned to connect the angles on the sides of the plates and attaching bars, and bolts securing the said clip angles and attaching bars to the angles on the sides of the plates.

7. In a collapsible and adjustable concrete form, the combination which comprises side plates having flanged ends with angles having outwardly extended perforated flanges secured to the side edges and with longitudinally disposed T-bars permanently secured to the plates and positioned midway between the angles on the side edges thereof providing an elongated shallow tray with a reinforcing member extended longitudinally through the center, attaching bars having mounting plates with studs extended from the sides thereof on one of the ends thereof, said studs positioned to register with the perforations of the flanges secured to the side edges of the plates and said attaching bars having perforated flanges and extended at right angles from the sides of said plates, clip angles positioned to connect the angles on the sides of the plates and attaching bars, and bolts securing the said clip angles and attaching bars to the angles on the sides of the plates.

8. In a collapsible and adjustable concrete form, the combination which comprises side plates having flanged ends with angles having outwardly extended perforated flanges secured to the side edges and with longitudinally disposed T-bars permanently secured to the plates and positioned midway between the angles on the side edges thereof providing an elongated shallow tray with a reinforcing member extended longitudinally through the center, attaching bars T-shape in cross section having webs with perforated flanges extended from one edge and from both sides of the webs and said flanges having spaced ribs on the surfaces opposite to the surfaces from which the webs extend and also having mounting extensions with studs thereon at one end and said studs positioned to register with perforations of the flanges on the sides of the plates, clip angles positioned to connect the angles on the sides of the plates and attaching bars, and bolts securing the said clip angles and attaching bars to the angles on the sides of the plates.
